[57] **CLAIM**

The ornamental design for a compact fluorescent lamp, as shown and described.

DESCRIPTION

FIG. 1 is a perspective view of a compact fluorescent lamp showing my new design;

FIG. 2 is a front elevational view thereof;

FIG. 3 is an elevational view looking from the right of FIG. 2;

FIG. 4 is a top plan view thereof; and

FIG. 5 is a bottom plan view thereof.

This article is a compact fluorescent lamp which incorporates a discharge tube, ballast etc. therein and can be lighted by threadably inserting it, like an incandescent lamp, into a socket.
